Inventor:

John O. Blythe

UNITED STATES PATENT OFFICE.

JOHN O. BLYTHE, OF PHILADELPHIA, PENNSYLVANIA.

IMPROVEMENT IN LAMP-BURNERS.

Specification forming part of Letters Patent No. 37,915, dated March 24, 1863.

To all whom it may concern:

Be it known that I, JOHN O. BLYTHE, of the city of Philadelphia, in the county of Philadelphia and State of Pennsylvania, have invented a new and useful Improvement on Coal-Oil Lamps; and I do hereby declare that the following is a full, clear, and exact description of the construction and operation of the same, reference being had to the annexed drawings, making a part of this specification, in which—

Figure 1 is a perspective view of the burner. No. 2, Fig. 2, is the collar to burner; No. 3, Fig. 3, the tube-plate, with hinge and catch; No. 4, Fig. 4, burner complete, attached to lamp.

In Fig. 1, S is the burner; a, the flange turned on at the top; G, the aperture; b, the thread cut on the neck of the burner; d, slit cut in the same for hinge to pass through and attach it to the tube-plate l; e, the slit cut in the lower part of the flange e for the catch m to pass through and hold the burner in its proper place.

In Fig. 2, K K are the lips of the collar turned over; h, screw-plate; G, aperture; and F F represent the collar.

In Fig. 3, o is the tube; l, the tube-plate; m, the catch; P, part of hinge fastened to the plate; n represents the hinge.

In Fig. 4, S is the burner; G, aperture; a, upper flange; K K, lips of collar; b, screw-thread; F F, collar; h, screw-plate; m, catch; n, hinge; e, flange; o, tube. The burner S has a narrow flange turned on at the top, and another turned up at the bottom, with two apertures cut in the burner for the reception of the hinge and catch, as seen in drawings; also, a thread cut on the neck of the burner. The collar has an aperture cut in it to fit on the burner. The edges of the collar at the aperture are filed down to an edge, and it is then

screwed down onto the burner (the neck of the burner rising above the collar, which is important to obtain draft) tightly, as seen in Fig. 4 in the drawings. This may be further secured by soldering. This collar, with plate and screw, together with the lips on the same, secures the chimney to the burner.

Fig. 3: the tube-plate is securely attached to the tube by soldering. The lip or catch passes up through the aperture cut in the burner, as seen in Fig. 4 at m. The hinge is passed over the flange or rim and through the aperture cut in the burner at d, as seen in Fig. 1 at d. By this arrangement the burner is securely attached, and can be lifted up for the purpose of trimming the wick. The tube is soldered to the screw in the top of the lamp, as seen in drawings. The hinge is soldered to the tube-plate, and may be riveted.

Fig. 4: The burner is here complete and attached to the lamp. Inside the rim and under the hinge, a piece of wire is secured to give strength to the same.

By the peculiar combination of the parts I obtain a superior light to any heretofore invented of this kind—that is, a round tube.

What I claim as my invention, and desire to secure by Letters Patent, is—

The peculiar construction of the burner S, in combination with the collar F F and the tube-plate l l, as combined with it, the tube, and attached to the screw in the top of the lamp, as seen in the drawings, or in Fig. No. 4, this burner having no perforations in its sides or wire-cloth, and rising above the collar and having a narrow flange turned over at the top, with screw cut upon it, as substantially described and set forth.

JOHN O. BLYTHE.
